(57) **CLAIM**

The ornamental design for the firearm magazine release, as shown and described.

DESCRIPTION

FIG. 1 is a first perspective view depicting an embodiment of a new design for a firearm magazine release.

FIG. 2 is a front view depicting an embodiment of a new design for a firearm magazine release.

FIG. 3 is a left view depicting an embodiment of a new design for a firearm magazine release.

FIG. 4 is a top view depicting an embodiment of a new design for a firearm magazine release.

FIG. 5 is a bottom view depicting an embodiment of a new design for a firearm magazine release.

FIG. 6 is a right view depicting an embodiment of a new design for a firearm magazine release.

FIG. 7 is a second perspective view depicting an embodiment of a new design for a firearm magazine release.

FIG. 8 is a third perspective view depicting an embodiment of a new design for a firearm magazine release.

FIG. 9 is a fourth perspective view depicting an embodiment of a new design for a firearm magazine release; and,

FIG. 10 is a front view depicting an embodiment of a new design of a firearm magazine release installed in an exemplary firearm.

The portions shown in broken line are for illustrative purposes only and form no part of the claimed design. Dash dot lines shown at the boundary between broken lines and solid lines are included to delineate claimed design from unclaimed portions thereof and of themselves are unclaimed portions of the design.

The short long short broken line(s) define the bounds of the claimed design and form no part thereof.
